[57] CLAIM

The ornamental design for an eyeglass frame, as shown and described.

DESCRIPTION

FIG. 1 is a perspective view of an eyeglass frame showing my new design;

FIG. 2 is a front view thereof;

FIG. 3 is a rear view thereof;

FIG. 4 is a top view thereof;

FIG. 5 is a bottom view; and,

FIG. 6 a right side view thereof (the left side view is symmetrical).

The broken line showing on the temple and temple tips is for illustrative purposes only and forms no part of the claimed design.
